UNITED STATES PATENT OFFICE.

SPENCER HEATH, OF BALTIMORE, MARYLAND.

PROPELLER-FORMING MACHINE.

1,325,671.

Specification of Letters Patent. Patented Dec. 23, 1919.

Application filed August 28, 1917. Serial No. 188,608.

To all whom it may concern:

Be it known that I, SPENCER HEATH, a citizen of the United States, residing at Baltimore, State of Maryland, have invented new and useful Improvements in Propeller-Forming Machines, of which the following is a specification.

This invention relates to machines for cutting material according to a pattern or 10 model and pertains particularly to machines for cutting aeroplane propellers.

The invention provides a stationary rotary cutter and a stationary rotary cam wheel mounted in specified fixed positions relative 15 to each other. A freely movable swinging extensible member is pivotally attached to a main upright support and carries at its outer end a yieldably mounted combined holder for a propeller model and the work which is 20 to be fashioned into a propeller. The work and model are held rigid with respect to each other and are adapted to be swung into engagement with the cutter and cam wheel respectively, movement of the cam wheel 25 over the helical surface of the model causing the cutter to form a corresponding surface in the work.

Other features and details of the invention will be described and claimed in the 30 following specification and claims and illustrated in the accompanying drawing in which—

Figure 1 represents an elevation of the machine showing the relative position of the 35 stationary parts and the swinging extensible member carrying the yieldably mounted model and work support.

Fig. 2 represents an enlarged sectional view of the upper bearing of the yieldably 40 mounted support.

Referring in detail to the drawings 1 represents a stationary post or support firmly fixed to suitable foundation or other substantial support. 2 represents an upper or 45 primary horizontally extending arm projecting from the support 1 and rigidly connected thereto. At the extreme end of the arm 2 is a rotary cutter member 3 mounted on a drive shaft 4 which extends through 50 the arm 2. At the opposite end of the shaft 4 is a pulley wheel 5 which is driven by belt 6 driven by motor 7. Immediately below the arm 2 and parallel therewith and extending in the same direction is a secondary 55 or lower arm 8 having at its end, immedi-

ately below the cutter wheel 3, a rotary cam wheel 9 rotatably mounted on a shaft 10 extending from the arm 8. The opposite end of the arm 8 is rigidly connected to the vertical supporting post 1.

The extensible arm is connected to the vertical supporting post 1 by hinged connections 11 and 12 and the extensible member swings therefrom as a rigid rectangular frame 13 comprising upper and lower horizontal portions and parallel vertical parts connecting the ends of the horizontal portion. At the side of the frame 13 opposite to the hinges 11 and 12, there is an additional rectangular frame 14 pivoted to the 60 top and bottom of the first rectangular frame, the top pivotal connection being denoted by 15 and the lower one by 16. The extreme outer vertical connecting member of the frame 14 is denoted by the numeral 65 17 and is formed of hollow tubular metal. A vertical rod 18 is slidably mounted within the tube 17 and extends from the top and bottom of the tube. At the top of the tube 17 a bearing is provided by the insertion of 70 the bearing member 19 through which the rod 18 extends. At the bottom of the tube 17 the tube is provided with a restricted opening forming similar bearing means for the rod 18. Within the bore of the member 75 17 and on the rod 18 is a shoulder 20 against which a spring 21 is adapted to bear. The opposite end of the spring 21 engages the inner surface of the restricted lower end of the member 17. At the top or upper portion 80 of the rod 18 is a shoulder 22 on which is a model 23 which is rigidly secured to the shoulder by any suitable fastening means 85 such as bolts or screws as indicated at 24. The rod 18 projects upwardly through the 90 model 23 and is adapted to receive at its upper end the material constituting the work as indicated by 25 which is to be formed into a product resembling the model. As illustrated herein this is to be formed 95 into a propeller. The work is spaced from the model 23 by means of a spacer member 26 which is slipped over the upper end of the rod 18 and which has a tight connection with the form or model 23 so that the part 100 26 may not turn on the rod 18 with respect to the model 23. At the upper end of the spacer member 26 is a shoulder 27 on which is firmly secured the work 25. The shoulder 105 27 may be secured to the under surface of 110

the work by means of angular projections extending into the wood or material or by means of screws or bolts. The upper side of the work is adapted to receive a clamp member 28 which is securely held in place by means of a fastening nut 29.

The model 23 is mounted so as to lie in substantially the same plane as the cam wheel 9 and the work 25 is spaced from the 10 model 23 at exactly the same distance as the distance between the cam wheel 9 and the rotary cutter 3. When the extensible arm is swung on the connections 11 and 12 and 15 and 16 the model 23 may be brought into 15 engagement with the cam wheel 9 and at the same time the rotary cutter 3 will operate on the material of the work and tend to fashion the latter according to the movement of the model over the cam. A vertical 20 yielding motion for the work, model and vertical rod 18 is provided by the resilient action of the spring 21 as it is compressed between the shoulder 20 and the lower end of the member 17. In the operation of the 25 machine pressure on the model or work will force the post 18 downwardly and if the extensible member is in the right position the work 25 will engage the cutter member 3. The machine has been found of great 30 service because of the freedom of movement provided by the extensible arm and the yieldably mounted model and work units. The work is rigid with respect to the model and the cutter member is rigid with respect 35 to the cam wheel. Any degree of vertical or horizontal movement may be secured by comparatively slight pressure on the work or model, this causing a corresponding movement in the swinging extensible member or the vertical movement of the work 40 and model. It is advantageous to have the peripheral contour of the cutter 3 and the member 9 similar. These members, however, need not have the same dimensions. 45 For instance it may be desirable to use a heavier thicker model than the one indicated at 23 in solid lines. In this case the thicker model is illustrated in dotted lines surrounding the original model 23. The 50 cam wheel 9 accordingly must be of smaller dimension than the one shown in full lines, the difference in size being in direct proportion to the enlargement of the model. The dotted lines within the wheel 9 show the relative size to correspond with the model as 55 enlarged in the model 23. The member 9 is preferably rotatably mounted but may be rigid on its support and not rotatable. The essential feature is that its contour 60 conform to the peripheral sweep of the cutter member.

The invention includes substitutes for the source of power and equivalent means for this as well as for the connecting drive belt.

65 Changes in material and size and shape of

parts may be made without departing from the scope of the invention.

What I claim is:—

1. In a machine of the character described, a primary stationary support, a rotary cutter member at one end of said support, a second stationary support, a follower member at one end of said second support and in a fixed position with respect to said cutter member, a third stationary support, 75 an extensible member pivotally attached at one end to said third stationary support and adapted to move in a given plane at right angles to the plane of rotation of the cutter member, and a combined work and model 80 holder mounted on said extensible member and adapted to swing work into engagement with said cutter member.

2. In a machine of the character described, a primary stationary horizontal support, 85 a rotary cutter member at one end of said support, a secondary stationary support, a rotary follower member mounted on one end of said secondary support and having its axis separate from but parallel with 90 and in the same vertical plane with the axis of said cutter member, a third stationary support, an extensible member pivotally attached at one end to said third stationary support to move in a given plane at right 95 angles to the plane of rotation of the cutter member, and a combined work and model holder mounted on said extensible member and adapted to swing work into engagement with said cutter member.

3. In a machine of the character described, a primary stationary horizontal support, a rotary cutter member at one end of said support, a secondary stationary support, a rotary follower member at one end of 105 said secondary support and in a fixed position with respect to said cutter member, said follower member and said cutter member being mounted to turn on their horizontal axes and in the same vertical plane, a 110 third stationary support, an extensible member pivotally attached at one end to said third stationary support to move in a given plane at right angles to the plane of rotation of the cutter member, and a combined work and model holder mounted on said extensible member and adapted to swing work into engagement with said cutter member.

4. In a machine of the character described, 120 a primary stationary horizontal support, a rotary cutter member at one end of said support, a secondary stationary support, a follower member at one end of said secondary support and in a fixed position with respect to said cutter member, a third stationary support, an extensible member pivotally attached at one end to said third stationary support to move in a given plane, and a vertically yieldable combined work and model 125 130

holder mounted on said extensible member and adapted to swing work into engagement with said cutter member.

5. In a machine of the character described, 5 a primary stationary horizontal support, a rotary cutter member at one end of said support, a secondary stationary support, a follower member at one end of said secondary support and in a fixed position with respect 10 to said cutter member, a third stationary support, an extensible member pivotally attached at one end to said third stationary support to move in a given plane, and a combined vertically yieldable work and model 15 holder mounted on said extensible member and adapted to swing work into engagement with said cutter member comprising a bearing in said extensible member, a slidably mounted rod extending from said bearing 20 and having means for holding a model and work in a parallel position and a yieldable spring member co-acting with said extensible member and said rod.

6. In a machine of the character described, 25 a primary stationary horizontal support, a rotary cutter member at one end of said support, a secondary stationary support, a follower member at one end of said secondary support and in a fixed position with respect 30 to said cutter member, a third stationary support, an extensible member pivotally attached at one end to said third stationary support to move in a given plane, and a combined vertically yieldable work and model 35 holder mounted on said extensible member and adapted to swing work into engagement with said cutter member comprising a bearing in said extensible member, a slidably mounted rod extending from said bearing 40 and movable at right angles to the path of movement of said extensible member, model fastening means rigidly attached to said rod, work fastening means on said rod arranged in a fixed position with respect to 45 said model fastening means, and a resilient spring member coacting with said extensible member and said rod.

7. In a machine of the character described, a primary stationary horizontal sup-

port, a rotary cutter member at one end of said support, a secondary stationary support, a follower member at one end of said secondary support and in a fixed position with respect to said cutter member, a third stationary support, an extensible member 55 pivotally attached at one end to said third stationary support to move in a given plane, a combined vertically yieldable work and model holder mounted on said extensible member for movement at right angles to 60 the plane of movement of said extensible member, and adapted to swing work into engagement with said cutter member, the mounting for said combined work and model holder comprising a bearing tube having an enlarged bore and reduced end openings constituting end bearings, a rod extending through said tube and projecting from either end, a shoulder on said rod adjacent 65 the upper end of said enlarged bore, a spring member within said enlarged bore encircling said rod, and adapted to engage said shoulder and be compressed between the same and the lower restricted end of said bearing tube, and fastening means on the 70 upper portion of said rod for fastening work rigidly to said rod.

8. In a machine of the character described, a primary stationary support, a rotary cutter member at one end of said support, a second stationary support, a follower member at one end of said second support and in a fixed position with respect to said cutter member, a third stationary support, an extensible member pivotally attached at 80 one end to said third stationary support and adapted to move in a given plane, said extensible member comprising a first rectangular frame pivotally attached at one side to said third stationary support, and a second 85 rigid rectangular frame pivotally attached to said first frame, and a combined work and model holder movably mounted on and with respect to said extensible member.

In testimony whereof I have hereunto set 95 my hand.

SPENCER HEATH.
